Fig. 5

FIGURE 1 is a front view in perspective of an attaché case showing my new design. The view from the rear is substantially identical except that the main panel is flat and undecorated.

FIGURE 2 is an end elevational view, reduced in scale, as seen from the left of FIGURE 1.

FIGURE 3 is a plan view.

FIGURE 4 is a front view in perspective, comparable to FIGURE 1, reduced in scale, and showing the attaché case with certain of the parts in altered position.

FIGURE 5 is a right hand end elevational view, reduced in scale, as seen from the right of FIGURE 4.

I claim:

The ornamental design for an attaché case, as shown and described.
